UNITED STATES PATENT OFFICE.

CHARLES MAHÉ DE CHENAL DE LA BOURDONNAIS, OF LOVENTOR MANOR, NEAR TOTNES, ENGLAND.

LOUD SPEAKER, GRAMOPHONE, AND OTHER SOUND RECORDING OR REPRODUCING APPARATUS.

Application filed July 19, 1926, Serial No. 123,506, and in Great Britain July 29, 1925.

This invention relates to loud-speakers, gramophones, or the like, that is to say analogous sound-recording or reproducing apparatus in general, and it has for its object so 5 to construct these apparatus that they may faithfully reproduce all sounds over an extended range.

It refers to apparatus of the kind comprising a large resonance chamber having a diaphragm (perforated or not) arranged in 10 front of said chamber in such a manner as to utilize the sound waves from both its outer and inner sides.

According to my invention the large resonance chamber is provided with a short, shallow, or dish-like horn, in order to increase the volume and provide a slight directional effect. This also provides for the necessary amount of damping to prevent any tendency of such a large diaphragm to "boom" 20 on the lower frequencies of audible sound. The horn and the resonance chamber may, if preferred, be formed in one, and the diaphragm would then be suitably supported 25 in front of, or within, the said chamber, and may have an annular space, aperture, or gap around it for the passage of the vibrations.

In a loud-speaker embodying my invention the large resonance chamber, which is made 30 of wood, or any other suitable material, and which may or may not be perforated, has placed over, or upon, it, a large diaphragm (or any suitable shape and material), and this latter is operated, say by the "centre-pull" 35 method, either electrically, or mechanically an aperture, or apertures, being provided, if desired, to permit both the efficient vibration of the centre part of the diaphragm and the ready communication of the vibrations of 40 the air enclosed within the resonance chamber, to the outer air.

The diaphragm may be operated from either the inside or the outside of the resonance chamber. A suitable diameter for said 45 chamber and diaphragm is about fifteen inches, but this measurement must, however, be governed by considerations of utility and volume required, and may be varied accordingly.

50 In order that the invention may be clearly

understood, and readily carried into effect, reference will now be had, by way of example, to the accompanying drawings in which:

Fig. 1 is a front view, and

Fig. 2 is a vertical section of an arrangement in which the short, shallow, or dish-like horn and large resonance chamber are formed in one, a more or less annular space, aperture, or vent being left around the edge of the diaphragm.

Fig. 3 is a front view of a similar arrangement, but in which the edge of the diaphragm is attached to the horn, and a circumferential ring of apertures is provided for the passage of the vibrations.

Fig. 4 is a fragmentary sectional view through one of such apertures, on a larger scale.

Fig. 5 is a vertical section of a modification in which the resonance chamber is partly 70 a separate structure secured in the back of the horn.

Referring more particularly to the example shown in Figs. 1 and 2:

a represents the resonance chamber whilst 75 *b* shows the diaphragm, which is carried by suitable supports *c*, such as small wood blocks, secured to the adjacent part of the horn *d*, and to the back plate or rear cover *d'*, of the resonance chamber.

e is the receiver for operating the diaphragm. This receiver is carried on the said back or rear cover *d'* and is connected with the centre of the diaphragm by a light rod *e'*, or in any convenient manner.

The shallow or dish-like horn *d* may be of octagonal shape as shown, and is formed of wood, wood-pulp, or other suitable material, as may also be the diaphragm itself. The apparatus is supported by a short pillar *f* 90 secured to the back *d'* and mounted on a pedestal *f'*.

The passage of the vibrations from the resonance chamber or space *a*, behind the diaphragm, is provided for by an approximately 95 annular opening, gap, or aperture, left between the edge of the diaphragm and the inner wall of the horn. The extent or outer limit of this gap or opening is indicated in Fig. 1 by the dotted line *b''*, which latter

marks the line where the diaphragm would, if it were large enough, meet the octagonal side walls of the horn.

The small supports c which carry the dia-

5 phragm are eight in number in the present example, to correspond to the number of sides of the horn. As they only take up very little space they do not interfere with the emission of sound from the resonance chamber.

10 It will be seen that the diaphragm b , and the back d^1 , of the resonance chamber, are approximately alike in size, and about three-fifths of the diameter of the horn at its front edge.

15 Moreover, the closed back d^1 serves as a reflector for the sound waves set up inside the resonance space or chamber, so that they pass out through the aforesaid annular aperture gap or vent (bounded by the line b^x) and supplement those emitted from the front of the diaphragm.

The horn with the back d' is substantially a truncated cone open at the base.

Thus the volume of the sound depends not 25 only on the vibrations emitted from the front of the diaphragm, but also, to an approximately equal extent, on those set up at the rear of the diaphragm in the resonance chamber.

30 In the arrangement shown in Figs. 3 and 4, practically the same construction is followed in principle, but the diaphragm is extended right across the inside of the horn parallel to the back d' and is secured thereto by a small lip or flange b^2 , suitable apertures b^1 being provided around it near its edge for the passage of the sound waves coming from the resonance chamber.

35 In the arrangement shown in Fig. 5, the diaphragm b is supported across a flanged ring or frame a^x which may be of truncated conical form, and which is secured to the back d^1 of the resonance chamber, and is provided with holes or vents b^1 all round it for the escape of the sound waves, a suitable gap of clearance being left all round between it and the inner wall of the horn.

Furthermore, the walls of the ring a^x may be made so thin as to communicate the vibrations from the back of the diaphragm to the outer air without the use of the holes.

40 In some cases the resonance chamber itself may be perforated either round the sides, or at the back, or both, as desired, for the freer emission of the sound.

45 It will be readily understood that a sound-recording or reproducing apparatus such as a loud-speaker, gramophone, or the like, according to this invention, approximately 60 doubles the volume of sound obtainable from any given diaphragm, in that the sound

waves emitted from the back thereof are reflected outwards together with those coming off the front of the diaphragm. Care is of course taken that the diaphragm b is situated at such a distance from the back d' of the resonance chamber that the reflected sound waves are sufficiently in phase with those coming off the front to preserve clarity of reproduction in conjunction with the increased volume obtained.

65 Although, in the examples illustrated, the horn has a uniform taper which extends to the back plate or sound-reflector d^1 , yet it will be readily understood that this is not a necessary arrangement, as the resonance chamber may be a cylindrical box fitted behind the tapered part of the horn, with the diaphragm extending across it at the junction of the two.

70 Obviously, the above arrangements may be modified in various ways in carrying the invention into practice without departing from the nature thereof.

75 Having now described my said invention, what I claim is:—

80 1. A loud speaker comprising a truncated conical horn closed at the truncated end thereof, a diaphragm supported parallel to the closed end and forming therewith a resonance chamber which is open to the open end 85 of the horn, and means for vibrating the diaphragm.

85 2. A loud speaker including a diaphragm, means to vibrate the same, and a shallow open vessel-like member, the bottom of which is flat and is in spaced relation to the diaphragm and forming therewith a resonance chamber, said chamber being open to the open end of the vessel.

90 3. A loud speaker including a diaphragm, means to vibrate the same, and a shallow open vessel-like member, the bottom of which is flat and is in spaced relation to the diaphragm and forming therewith a resonance chamber, said chamber being open peripherally to the 105 open end of the vessel.

95 4. A loud speaker comprising a truncated conical horn closed at the truncated end thereof, a plurality of supports attached to the walls thereof adjacent the bottom and in 110 spaced relation peripherally thereof, a diaphragm supported by the latter and providing with the closed end of the horn a resonance chamber, said resonance chamber being open at the periphery of the diaphragm and 115 between the supports, and means for vibrating the diaphragm.

100 In witness whereof, I have hereunto signed my name.

CHARLES MAHÉ de CHENAL de la
BOURDONNAIS, Prince de Mahé.
